UNITED STATES PATENT OFFICE.

SAMUEL A. MOTHERAL, OF CINCINNATI, OHIO.

VEHICLE-WHEEL.

SPECIFICATION forming part of Letters Patent No. 569,118, dated October 6, 1896.

Application filed August 26, 1895. Serial No. 560,561. (No model.)

To all whom it may concern:

Be it known that I, SAMUEL A. MOTHERAL, a citizen of the United States, and a resident of Cincinnati, in the county of Hamilton and 5 State of Ohio, have invented certain new and useful Improvements in Vehicle-Wheels, of which the following is a specification.

My invention is an improved vehicle-wheel. Its object is to provide the wheel itself with 10 a wrench attachment by which the wheel may be removed and replaced, the attachment also serving to prevent sand, dirt, or other extraneous matter from getting into the hub and injuring the bearings.

15 The invention consists, essentially, in the wrench-head applied to or formed integral with the hub point-band of the wheel, the jaws of the wrench being readily thrown in to grasp the axle-nut, so that by turning the 20 wheel the nut may be unscrewed or tightened up to place, and when screwed in position, the wrench-head being thrown back, closes the front opening in the point-band.

25 The invention will be first fully described in connection with the accompanying drawings, and then particularly referred to and pointed out in the claims.

Referring to the drawings, in which like 30 parts are indicated by similar reference-letters wherever they occur throughout the various views, Figure 1 is a front or end elevation of a hub point-band with my improvement attached. Fig. 2 is a side elevation of the front 35 portion of the band. Fig. 3 is a transverse section through the band, showing the attachment in side-elevation. Fig. 4 is a diametrical section taken through the point-band upon the line $x x$ of Figs. 1, 2, and 3, showing the 40 axle-nut and a portion of the hub and axle in dotted line. Fig. 5 is a similar view taken at a right angle to the view shown in Fig. 4.

Fig. 6 is a view similar to Fig. 4, but with the wrench-head swung upon its pivot to grasp the axle-nut. Fig. 7 is a view similar to Fig. 45 5 with the wrench-head thrown in position to operate the nut. Fig. 8 is a view similar to Fig. 6, but with the wrench-jaw omitted to expose the spring which retains the wrench member in the closed position, as seen in Figs. 50 1, 3, 4, and 5. Fig. 9 is a front elevation of the point-band, illustrating a modification of my invention. Fig. 10 is a diametrical sec-

tion of the same through line $y y$ of Fig. 9, with the wrench-head shown closing the opening to the point-band. Fig. 11 is a similar 55 view with the wrench-head thrown to its operative position. Figs. 8, 9, 10, and 11 are drawn on a diminished scale.

The simplest form of my invention is illustrated in Figs. 1 to 8, inclusive. 60

A represents a point-band of ordinary construction, in the outer end of which is secured a disk B. This disk is perforated to receive the wrench-head C, which is fitted to swing within the disk upon a steel pin D, 65 which passes through the point-band, the walls of the disk B, and the wrench-head C. The inner walls of the disk and the outer walls of the wrench-head are beveled counter to each other to permit the wrench-head to 70 swing around and bring its jaws c to embrace the angular sides of the axle-nut E, as clearly seen in Figs. 6, 7, and 11, and to completely close the opening in the disk B when swung to the closed position, as seen in Figs. 1, 3, 5, 75 9, and 10.

For the purpose of retaining the wrench-head with slight friction and without rattling in either position I have provided coil-springs d, which coil around the pin D at each end 80 in countersunk recesses in the disk B and wrench-head C. These springs are not, however, essential to the operation of the device and may be omitted.

To the inner face of the tongue b and the 85 disk B, which tongue, when the wrench-head is in the closed position, passes between the jaws c, is secured the U-shaped spring F, the ends of which are bent in the form of a spring-latch to clasp over the inner wall of 90 the jaws c and retain the wrench-head in place when closing the opening in the disk B, as clearly seen in Figs. 3, 4, and 10.

The parts being fitted together, as shown 95 in the drawings, and it being desired to remove the wheel, it is only necessary to turn the wrench-head to the position shown in Figs. 6, 7, and 11 to throw the jaws of the wrench upon opposite sides of the nut, and by taking hold of the spokes or rim of the 100 wheel and turning it the nut will be unscrewed, and after the axle is oiled the nut is replaced in the same manner, the wrench will be swung upon its pivot to close the

opening in the disk B, and thus prevent sand or other extraneous matter entering the point-band.

In the modification shown in Figs. 9 to 11, 5 inclusive, the inner wall of the disk B' is recessed, and the jaws c' and part of the wrench-head adjacent to them are rabbeted to fit snugly against the inner recessed portion of the rim when the jaws are closed, as seen in Fig. 10, so that no dust of any kind can pass 10 between the joint formed by the wrench-head and disk when the wrench is thrown to its closed position.

It is obvious that the wrench-head holder 15 or disk B and point-band may be formed integral, but the form shown is deemed the best, as in such form the improvement may be readily applied to any of the vehicle-wheels now in common use. The form of the wrench-head and opening in the disk to receive it 20 may be also varied without departing from the principle or scope of my invention. In fact, the wrench-head may be pivoted directly to the point-band without the intervention of the disk B, which, in combination with said 25 head, forms also a sand band or cap closing the front of the point-band.

It is also obvious that if the tension of the springs d be made strong enough the springs 30 F may be omitted.

What I claim as new, and desire to secure by Letters Patent, is—

1. In a vehicle-wheel, the combination of 35 the hub point-band, and a wrench-head pivoted within said band, and adapted, when turned upon its pivot in one direction, to em-

brace the axle-nut, whereby when the wheel is turned, the nut is either unscrewed or screwed up, substantially as shown and described.

2. The combination, in a vehicle-wheel, of 40 the point-band, a disk fitted in the outer end of said band, a wrench-head fitting the perforation in said disk, and a pivot for the wrench-head upon which it is swung in one 45 direction to engage the axle-nut, and in the reverse direction to release the nut and close the point-band, substantially as hereinbefore set forth.

3. The combination of the hub, the point- 50 band secured thereto, the perforated disk fitted within the outer end of said point-band, a wrench-head swiveled in said opening and adapted, when in the normal position, to close the same, and when turned upon its pivot to 55 embrace the axle-nut, and the spring-catch to hold said head in its normal position, substantially as shown and described.

4. The combination, in a vehicle-wheel, of 60 the point-band, the perforated disk fitted in the outer end of said band, a wrench-head fitted in said disk, the pivot-pin passing through said band, disk and wrench-head, said head and disk having countersunk perforations around the pivot-pin, and a coiled 65 spring around the pivot-pin seated in said countersunk perforations, substantially as shown and described.

SAMUEL A. MOTHERAL.
